UNITED STATES PATENT OFFICE.

JOSEPH SEARS, OF CHICAGO, ILLINOIS.

IMPROVEMENT IN SOLDERING-TOOLS.

Specification forming part of Letters Patent No. 152,770, dated Ju'y 7, 1874; application filed April 7, 1874.

CASE B.

To all whom it may concern:

Be it known that I, JOSEPH SEARS, of the city of Chicago and county of Cook, in the State of Illinois, have invented certain new and useful Improvements in Soldering Apparatus, of which the following is a specification.

These improvements relate primarily to the invention described in Letters Patent of the United States, No. 137,244, issued to me on the 25th day of March, 1873. The specification of this patent describes a soldering-tool having a hollow tip or copper, within which a heating-jet is sustained by properly-mingled gas and air, conducted into the tip-cavity by an axial handle-tube. The present invention consists, first, in a plug or nipple of gas-pipe applied to the tip in any approved way, in combination with a coupling-collar, by which the tip and plug are attached to the handle-tube, so as to be readily removed therefrom when a new tip is required. The invention consists, secondly, in a shield or deflector formed on the coupling-collar, and supported thereby behind the tip. The invention consists, thirdly, in a rest or holder for employment in combination with a shield or deflector behind the tip. The invention consists, fourthly, in a sheathing or coating of tin plate applied within the dies to protect the rear end of the tip or copper from oxidation.

Figure 1 is a vertical longitudinal section, illustrating the first three parts of this invention. Fig. 2 is a perspective view of the rest or holder. Fig. 3 is an elevation of a portion of the tool, illustrating some slight modifications. Fig. 4 is a full side elevation of another tool, illustrating the fourth part of the invention and certain modifications in the subject-matter of the first part of the invention. Fig. 5 is a longitudinal section of the same on a larger scale. Fig. 6 is a transverse section on the line 6 6, Fig. 5.

Like letters of reference indicate corresponding parts in the several figures.

The soldering-tool, which is the primary part of this apparatus, consists of a hollow tip or copper, A, a wooden handle, B, an axial handle-tube, C, a plug or nipple, D, attached to the tip, and a coupling-collar, E,

for attaching the plug and tip to the handle-tube, with or without a shield or deflector, F, formed on the coupling-collar, as illustrated in Figs. 1 and 4. The other part of the apparatus consists of a holder or rest, H, Figs. 1 and 2, to receive and support the tool when out of use, and to co-operate with the internal jet and the shield or deflector F, to protect the copper from oxidation and to economize heat. The hollow tip or copper A may be of any approved external shape and dimensions, and may be manufactured by any approved process. The flame-cavity z is adapted to receive one end of the plug or nipple D within it, and the latter is of small size, of gas-pipe, and in the illustration is screwed into the rear end of the tip. This construction is the subject-matter, in part, of another specification of even date herewith, where it is fully described.

In order to obviate any difficulty which users might have in withdrawing the plug from a worn tip when a new one is required, the coupling-collar D is provided as means for attaching the plug and tip to the handle-tube, so that they may be readily removed together. Tips with plugs applied will be furnished by the manufacturer, and the scrap-copper and old plugs may be separated and saved at leisure.

For the reception of this collar the tip end of the handle-tube C is turned down, and a short screw-thread is cut at the proper point, as illustrated in Figs. 1, 5, and 6; or the thread may extend back from the end, as illustrated in Fig. 3. The collar has a corresponding internal thread. To engage with the plug the collar is provided with a single set-screw, x, as illustrated in Fig. 1, but two or more screws, x², may be employed, as illustrated in Fig. 3; or the socket portion of the collar may be threaded, and the plug adapted thereto, as illustrated in Figs. 4 and 5, and in this case the thread on the two ends of the plug may be continuous, as represented, or interrupted. The shield or deflector F, broadly considered, is the subject-matter, in part, of the specification of even date herewith, to which reference has hereinbefore been made.

Supported in the manner herein described,

the shield or deflector imparts its advantages without multiplication of parts. The same operates to protect the hand, to turn back the products of combustion, so as to cause them to envelop the tip, to prevent oxidation, and to economize heat. It also serves to throw the heat upon the work, so as to facilitate the soldering operation. To co-operate therewith for protecting and heating the tip, as well as to conveniently receive and hold the tool while out of use, the holder or rest H is provided. This consists of a horizontal tube, h, with a single central leg, l, adapted to occupy a hole in the bench I when the holder is required. The tube h comprises a flaring rear end to receive the tip and shield, and to closely embrace the latter, a middle section, cylindrical or bulging in shape, and a contracted front end, through which the products of combustion escape when the tool is in the holder.

When the surface of the bench is required, the holder may readily be taken out and laid aside.

The handle B may be wholly of wood, and tightened and strengthened by a wire, y, as represented.

The handle-tube C extends through the handle, and projects sufficiently to receive the end of a flexible conducting-tube, J, as illustrated in Fig. 1.

To render the tip A temporarily self-protected against oxidation, a sheathing or coating, a, Figs. 4 to 6, is applied to the rear end of the tip during its manufacture. This sheathing or coating consists of tinned sheet-iron

applied within the dies. The point of the tip becomes tinned in use, and thus protected.

The following is claimed as new in this invention, namely:

1. The coupling-collar E, applied to the handle-tube, in combination with the plug or nipple D of small gas-pipe, applied internally to the hollow tip A, said coupling-collar serving to attach the said plug to the handle-tube, so that the plug and tip may be readily removed and replaced together, in the manner herein set forth.

2. The combination of the hollow tip A, plug or nipple D, handle-tube C, coupling-collar E, and shield or deflector F, the latter being formed on said collar and supported thereby, as herein shown and described.

3. The rest or holder H, in combination with a soldering-tool having a hollow tip with a heating-jet within the same, and a shield or deflector, F, behind the tip, substantially as herein shown and described, for the purposes set forth.

4. A tip or copper, A, having a sheathing, a, of tin plate applied to its rear end during its manufacture, substantially as herein described, to protect the same against oxidation, as set forth.

In testimony of which invention I hereunto set my hand this 27th day of March, 1874.

JOSEPH SEARS.
